UNITED STATES PATENT OFFICE

GEORGE T. JOHNSON AND HARRY W. STERTZBACH, OF COLUMBUS, OHIO, ASSIGNEES TO
THE BUCKEYE STEEL CASTINGS COMPANY, OF COLUMBUS, OHIO

CAR-TRUCK SIDE FRAME

Application filed May 24, 1928. Serial No. 280,315.

This invention relates to car trucks of the "inboard" type in which the side frames and journal boxes are arranged inwardly in respect to the car wheels, and the primary object is to provide a side frame of such design that ample clearance for standard brake beams will be attained. Another object is to provide a construction which will permit the brake beams to be applied or taken down without removing the brake heads from the beams, and also provide a safety support whereby the brake beam will be prevented from dropping onto the track rails and causing derailment if a brake hanger should break. The invention also seeks to provide a structure which will effectually withstand the stresses imposed by use and which may be economically manufactured. The invention is illustrated in the accompanying drawings and will be hereinafter fully described and particularly defined.

In the drawings,

Figure 1 is a side elevation of a side frame embodying the invention;

25 Figure 2 is a top plan view of the same;

Figure 2a is a bottom plan view thereof;

Figure 3 is a central transverse section;

Figures 4 and 5 are detail sections taken on the lines 4-4 and 5-5, respectively, of

30 Fig. 1;

Figure 6 is a detail end elevation;

Figures 7, 8, 9 and 10 are detail sections taken, respectively, on the lines 7-7, 8-8, 9-9 and 10-10 of Fig. 1.

35 In the drawings, the numeral 1 designates the top or compression member, 2 the bottom or tension member, and 3 the columns of a side frame connecting the top and bottom members, the car wheels in the fully assembled and mounted truck being arranged outwardly from the side frame, as indicated by the dotted lines in Fig. 3. The columns are straight and vertical on their opposed faces whereby the bolster opening defined by the

40 columns and the top and bottom members will be of uniform width through its entire height so that the assembling of the side frames with the truck bolster will be facilitated and straight movement of the end of the bolster

45 into the bolster opening will bring the parts 50 into the proper relation. It will also be noted upon reference to Fig. 3, that the top of the side frame, over the truck bolster opening slopes inwardly, thereby providing ample clearance between the side frame and the car bolster. The spring seat member 4 is located between the lower ends of the columns, and it will be noted, particularly upon reference to Fig. 1, that the top and bottom of the tension member are in horizontal planes extending to points well beyond the columns from which points the tension members curve upwardly, as at 5, to merge into straight upwardly inclined portions 6. From the straight portions 6 side plates 7 rise to merge into the top or compression member, as shown in Fig. 1, said plates extending to the ends of the side frame. The innermost edges, 8, of these side plates extend upwardly to the top member on lines nearly at a right angle to the respective straight portion 6 of the bottom member and are reenforced by ribs or flanges 9 on their inner sides. Large openings 10 are thus formed through the side frame at the outer sides of the columns 3 through which the brake beams are accessible so that the brake beams may be applied or taken down without removing the brake heads from the beams.

The ends of the brake beams pass through these openings so that if a brake hanger should break, the tension member of the side frame, which is underneath the brake beam, will constitute a safety support and prevent the beam dropping to the track and derailing the car, it being noted that the brake hanger brackets 11 are located at the top of the respective openings 10. To reduce weight openings 12 are formed through the side plates 7 near the top or compression member and to avoid loss of strength reenforcing ribs or flanges 13 are formed on the inner faces of the plates around said openings.

The previously mentioned curved formation of the tension member causes bending stresses to be set up, and there is also a tendency toward high unit fibre stresses on the concave side of the member. To counteract this condition and provide an efficient distribution of metal throughout the curved

part, it is desirable to have a considerable area to absorb the direct tensile stress and to also have the centre of gravity as close to the concave side of the member as possible. The 5 tension member is of box form in cross section, as shown in Fig. 3, and extending longitudinally thereof is a central rib 14 which terminates just beyond the curved portions of the member, the sides and bottom of the 10 box terminating near the upper ends of the straight portions 6, and through the lower portions of said rib are openings 15 which tend to throw the locus of centers of gravity toward the concave side. As the load is 15 placed upon the spring seat 4 and supported at the journal centers, the top or compression member may be considered as a beam deflecting in unison with the bottom or tension member, and the vertical members, including 20 the side plates 7 and the columns 3, are hangers joining the bottom member with the top member.

In order to have the most efficient action and derive maximum support from the top 25 member as a beam the hangers should be of a form most suitable for taking axial loads. For this reason, the construction shown in Fig. 10 and previously described is employed, the same furnishing suitable edges to withstand any secondary bending stresses which 30 may be set up in the side plates due to differences in flexure between the top and bottom members. For the same reason, the columns 3, as shown in Figs. 7 and 8 are of channel 35 type with their side webs turned away from the bolster opening and provided with inwardly projecting ribs or flanges 16 along their edges, providing maximum area consistent with the spacing available and favorable manufacturing conditions. In their 40 lower portions, the columns have their flanges 16 united by a web 17 and corner ribs 18 connect the columns with the outer portions of the spring seat.

The ends of the frame are arched to span 45 the journal boxes and are constructed with grooves 19 to engage the same, and the crown of the arch is box-like in cross section, as shown in Fig. 5 to attain the necessary 50 strength. To reduce weight, the extremities of the frame are cut away as indicated at 20.

Having fully described our invention what we claim as new and desire to secure by Letters Patent, is:—

55 1. A side frame comprising a top member, a bottom member, and columns connecting said members, the bottom member extending horizontally across the lower ends of the columns to points beyond the columns and 60 then curving upwardly, and a central longitudinal rib between the top and bottom walls of the curved portion of the bottom member.

65 2. A side frame comprising a top member, a bottom member, and columns connecting said members, the bottom member extending

horizontally across the lower ends of the columns to points beyond the columns and then curving upwardly, and a central longitudinal rib between the top and bottom walls of the curved portion of the bottom member, 70 said rib having openings through its outer portion.

3. A side frame comprising a top member, a bottom member, and vertical members connecting the top and bottom members, said vertical members being reinforced at their lower ends by a central vertical longitudinal rib which extends into said vertical members. 75

4. A side frame comprising a top member, a bottom member, and columns connecting said members, the bottom member being straight between the columns and the columns being of channel formation with their side members directed outwardly and provided with reentrant ribs on their inner faces along their edges over the whole length of the collar. 80

85 5. A side frame comprising a top member, a bottom member having a web with an upturned end, and columns connecting said members, the bottom member being straight between the columns and the columns being of channel formation with their side members directed outwardly and provided with reentrant ribs on their inner faces along their edges which connect with the upturned end of the bottom member web. 90

95 6. A side frame comprising a top member, a bottom member, columns connecting said members, the bottom member being straight between the columns and curving upwardly beyond the columns, and upwardly converging inclined hanger elements connecting said top and bottom members and spaced outwardly from the columns whereby to define an opening through which a brake beam may be passed. 100

105 7. A side frame comprising a top member, a bottom member, straight columns connecting said members and defining therewith a bolster opening of uniform width, and upwardly converging inclined hanger elements connecting the top and bottom members and spaced longitudinally of the frame from the 110 columns. 115

120 8. A car truck side frame including a compression member, a tension member, the ends of said members merging into each other and forming arc-shaped ends for the side frame, columns connecting said members, and hanger elements connecting said members and spaced outwardly from the columns, whereby to define pairs of openings, some of said openings permitting the brake beams to be passed therethrough, each of said last mentioned openings being of substantially the same height as the opening between the columns, and being of only slightly less width than the opening between the columns. 125 130

9. A car truck side frame as claimed in claim 8, including brake hanger brackets projecting laterally from the side frame, and arranged substantially centrally over the 5 openings defined by the columns and hanger elements.

10. A side frame for car trucks, comprising a top member, a bottom member and vertical members connecting the top and bottom 10 members, the bottom member having its end portions extending in opposite directions and merging into the ends of the top member, said side frame having a bolster opening between the vertical members, and brake beam 15 openings at opposite sides of the vertical members, each of said openings being substantially equal in area to each of the other openings, upwardly converging hanger elements connecting the top and bottom members 20 and defining the outer walls of the brake beam openings, and webs extending from the hanger elements to the ends of the side frame.

In testimony whereof, we have signed this specification.

25 GEORGE T. JOHNSON.
HARRY W. STERTZBACH.

DISCLAIMER

1,741,845.—*George T. Johnson and Harry W. Stertzbach, Columbus, Ohio.* CAR-
TRUCK SIDE FRAME. Patent dated December 31, 1929. Disclaimer filed
March 17, 1932, by the assignee, *The Buckeye Steel Castings Company*.

Hereby enters this disclaimer to that part of the claims in said specification which are in the following words, to wit:

“5. A side frame comprising a top member, a bottom member having a web with an upturned end, and columns connecting said members, the bottom member being straight between the columns and the columns being of channel formation with their side members directed outwardly and provided with reentrant ribs on their inner faces along their edges which connect with the upturned end of the bottom member web.

“6. A side frame comprising a top member, a bottom member, columns connecting said members, the bottom member being straight between the columns and curving upwardly beyond the columns, and upwardly converging inclined hanger elements connecting said top and bottom members and spaced outwardly from the columns whereby to define an opening through which a brake beam may be passed.

“7. A side frame comprising a top member, a bottom member, straight columns connecting said members and defining therewith a bolster opening of uniform width, and upwardly converging inclined hanger elements connecting the top and bottom members and spaced longitudinally of the frame from the columns.

“8. A car truck side frame including a compression member, a tension member, the ends of said members merging into each other and forming arc-shaped ends for the side frame, columns connecting said members, and hanger elements connecting said members and spaced outwardly from the columns, whereby to define pairs of openings, some of said openings permitting the brake beams to be passed therethrough, each of said last mentioned openings being of substantially the same height as the openings between columns, and being of only slightly less width than the opening between the columns.

“9. A car truck side frame as claimed in claim 8, including brake hanger brackets projecting laterally from the side frame, and arranged substantially centrally over the openings defined by the columns and hanger elements.

“10. A side frame for car trucks, comprising a top member, a bottom member and vertical members connecting the top and bottom members, the bottom member having its end portions extending in opposite directions and merging into the ends of the top member, said side frame having a bolster opening between the vertical members, and brake beam openings at opposite sides of the vertical members, each of said openings being substantially equal in area to each of the other openings, upwardly converging hanger elements connecting the top and bottom members and defining the outer walls of the brake beam openings, and webs extending from the hanger elements to the ends of the side frame.”
